L. A. SALTHOUSE.
SAFETY LAMP CHIMNEY AND HOLDER.
APPLICATION FILED MAY 15, 1916.

1,218,703.

Patented Mar. 13, 1917.

UNITED STATES PATENT OFFICE.

LAURA ALLICE SALTHOUSE, OF CUYAHOGA FALLS, OHIO.

SAFETY LAMP-CHIMNEY AND HOLDER.

1,218,703.

Specification of Letters Patent. Patented Mar. 13, 1917.

Application filed May 15, 1916. Serial No. 97,676.

To all whom it may concern:

Be it known that I, LAURA ALLICE SALTHOUSE, a citizen of the United States of America, residing at Cuyahoga Falls, in the 5 county of Summit and State of Ohio, have invented certain new and useful Improvements in Safety Lamp-Chimneys and Holders, of which the following is a specification, reference being had therein to the accompanying drawing.

This invention relates to a safety lamp chimney and holder and has for its principal object the production of a simple and efficient means for positively holding the chimney 15 upon the burner and preventing the same from being accidentally displaced therefrom.

Another object of this invention is the production of a safety lamp chimney and holder wherein the arms of the holder are constructed so as to bear upon the side portions of the chimney under normal conditions for holding the chimney against accidental displacement, these arms being capable of being swung outwardly at their 25 upper ends so as to disengage the chimney and permit the same to be removed from engagement with the burner.

Another object of this invention is the production of a safety lamp chimney and holder wherein the holder comprises a plurality of arms carried upon the burner so as to normally extend in vertical positions, these arms being provided with sockets in which 35 knobs formed upon the chimney are adapted to fit so as to hold the chimney against accidental displacement, these arms being mounted so as to be sprung outwardly from engagement with the chimney and thus permit the chimney to be removed as desired.

With these and other objects in view this invention consists of certain novel combinations, constructions, and arrangements of parts as will be hereinafter fully described 45 and claimed.

In the accompanying drawing:

Figure 1 is a side elevation of the safety lamp chimney and holder, illustrating the same in use, the chimney being broken away.

50 Fig. 2 is a side elevation of one of the arms, illustrating the same partially in section, showing how the same is mounted upon the burner.

Fig. 3 is a section taken on the line 3—3 of 55 Fig. 1.

Fig. 4 is a detail perspective view of a slightly modified form of one of the arms.

Fig. 5 is a fragmentary side elevation of a portion of the chimney, showing one of the knobs mounted thereon.

Referring to the accompanying drawings by numerals it will be seen that the chimney 1 is adapted to be mounted upon the base 2 of the burner 3 in the usual manner. This chimney 1, however, is provided with a plurality of lugs 4 formed thereon having flat sides 5 for purposes to be hereinafter set forth.

The holder comprises a plurality of arms 6 having a bowed lower portion 7 from 70 which extends a horizontal finger 8. The base 2 of the burner 3 is provided with a strap 9 struck therefrom and being offset downwardly, as shown in Fig. 2, so as to permit the finger 8 to extend therethrough.

75 This finger 8 is provided with a lip 10 at its inner end bearing upon the inner side of the strap 9 thus holding the arm 6 upon the burner when in use. Owing to the fact that the base 2 of the burner 3 is 80

comparatively flat the finger 8 fits snugly thereon and is retained in position by means of the strap 9. It will be seen that the finger will be held normally in a vertical plane, as shown in Figs. 1 and 2. The arm 85

6 is provided with an outwardly punched portion 11 thereby forming an internal socket 12, while the extreme upper end of the arm 6 is bent outwardly as indicated at 13 to provide a directing portion for directing the lower end of the chimney 1 in between the arms when the device is in use. A depending bar 14 is formed integral upon the bowed portion of the arm 6 and extends for a considerable distance below the finger 90 95 8 so as to support the bearing buttons 15.

When this device is in operation it will be seen that a number of the arms are carried upon the base 2 of the burner 3. As disclosed herein it is preferably desired to 100 employ two arms so that one arm may be operated by the thumb of one hand, while the remaining arm may be operated by the third finger of the same hand. Therefore, the arms of the holder should be carried in 105 alinement with each other upon opposite sides of the burner, although, of course, it is necessary to employ the secondary stationary arms 16' now in ordinary use upon burners so as to engage the chimney 1 at 110

points intermediate the arms 6. If it is desired, however, any number of arms as shown in this invention may be employed, although, as above stated, it is only necessary to employ two. The lower end of the chimney 1 is directed between the arms 6 of the holder by the upper outwardly bent ends 13. When the lower end of the chimney rests upon the base 2 it will be seen that the 10 knobs 4 will be carried in the sockets 12 of the arms 6. The outer sides 4' of the knobs 4 are beveled outwardly toward a point adjacent the surface of the lamp chimney 1, thereby permitting the knobs to easily ride 15 in between the arms, forcing the same outwardly as the chimney is moved downwardly. Finally these knobs 4 will pass into the sockets 12 and will fit snugly therein inasmuch as the shape of the lugs will conform 20 to the shape of the sockets and accordingly, the sides 5 of the lugs will hold the chimney from tipping upon the burner. When it is desired to release the chimney the bearing buttons 15 may be gripped by the thumb and 25 the third finger of the operator's hand and being urged toward each other the upper ends of the arms will be swung outwardly from engagement with the chimney, as indicated by dotted lines at one of the arms in 30 Fig. 1, thus causing the knobs 4 of the lamp chimney 1 to be removed and freed from the sockets 12 and at this time it is obvious that the chimney may be removed. As soon as 35 the buttons 15 are released, however, the arms will swing back to their normal vertical positions for it will be seen that the same are formed upon the fingers 8 so as to cause the resiliency of the arms and the fingers to normally retain the arms in a vertical position and, therefore, when sufficient pressure is brought to bear upon the arms they will 40 be swung against the tension of the fingers 8.

By referring to Fig. 4 it will be seen that a slightly modified form of arms has been 45 disclosed in which the arm as shown is formed from a single sheet of material. This arm 16 has the bulged portion 17 from which depends the bar 18. The finger 19 is struck from the bar 18 so as to extend at 50 right angles to the finger 16 of the bar 18. This finger 19 is provided with a lip 20 for holding the same upon the burner in a manner similar to which the finger 8 of the preferred form is retained. The lower end of 55 this bar is rolled to provide the bearing sleeve 21 upon which pressure is applied when it is desired to swing the arm 16 from engagement with the lamp chimney 1. This arm 16 is provided with an outwardly struck

tongue 22 which is bent so as to form a receiving socket 23, while the upper end of the arm is bent outwardly as shown at 24. The operation of this modified form of the arm is similar in all respects to the operation of the preferred form. The only difference in 60 the construction resides in the fact that instead of punching the arm to provide a socket the tongue 22 is struck outwardly and bent to form a socket, while the lower end of the arm is rolled so as to provide the bearing sleeve 21. It is, of course, obvious by referring to Fig. 2 that the finger 8 is struck from the depending bar 14 when the arm is being constructed so that this arm will also be formed from a single strip of material 65 with the exception of the bearing buttons 15.

From the foregoing description it will be seen that a very simple and efficient holder has been provided for a lamp chimney which is provided with sockets in its arms so as 70 to receive the knobs upon the sides of the chimney for holding the chimney in a set position upon the burner. It will further be seen that the arms are formed from blank sheets of material thereby causing the 75 same to be more positively held in a set position without danger of injury thereto, while the fingers being struck from the arms will form a resilient support for normally retaining the arms in a vertical position for 80 retaining the chimney when the same is in operation, although it will be seen that by the small pressure applied to the arms, the arms may be swung outwardly for releasing 85 the chimney.

What is claimed is:—

1. A lamp chimney holder comprising a plurality of resilient arms, each arm having a bowed lower portion, a depending bar formed upon said bowed lower portions, a 100 finger struck from said bar and extending at right angles thereto, said finger being adapted to be secured to a burner, grip means formed upon the lower end of said bar, and retaining means formed upon said 105 arms.

2. A one-piece resilient lamp chimney holder comprising an arm, a bar depending from said arm, a finger struck from said bar and extending to one side thereof, said finger being adapted to be secured to a burner, the lower end of said bar being rolled to form a bearing sleeve, and a chimney gripping means formed upon said arm.

In testimony whereof I hereunto affix my 115 signature.

LAURA ALLICE SALTHOUSE.
